UNITED STATES PATENT OFFICE.

FRANCIS W. DEAN, OF CAMBRIDGE, MASSACHUSETTS.

COMPOUND ENGINE.

SPECIFICATION forming part of Letters Patent No. 433,164, dated July 29, 1890.

Application filed May 29, 1890. Serial No. 353,579. (No model.)

To all whom it may concern:

Be it known that I, FRANCIS W. DEAN, of Cambridge, in the county of Middlesex and State of Massachusetts, have invented certain new and useful Improvements in Compound Engines, of which the following, taken in connection with the accompanying drawings, is a specification.

My invention relates to compound engines of that class in which in starting live steam is simultaneously admitted to both cylinders in order to obtain greater pressure at starting, and also to obviate the difficulty sometimes met of having to apply manual power to start the engine when steam is admitted first to the high-pressure cylinder only, and the high-pressure crank happens to be on one of its dead-centers.

The objects of my invention are to automatically regulate the admission of live steam to the low-pressure cylinder in starting, and to automatically cut off the supply of live steam to said low-pressure cylinder when the crank-shaft commences to revolve; and it consists in certain novel features of construction, arrangement, and combination of parts, which will be readily understood by reference to the description of the drawings and to the claims hereinafter given, and in which my invention is clearly pointed out.

Figure 1 of the drawings is a vertical transverse section through the smoke-box of a locomotive-boiler and the two steam-cylinders of a compound engine illustrating my invention on line $\alpha\alpha$ on Fig. 2. Fig. 2 is a plan of the saddles and the steam-cylinders with the steam-chests and covers removed. Fig. 3 is a central longitudinal section through a portion of the boiler-shell on line 1 1 on Fig. 1, and through a portion of the steam-pipe leading from the high-pressure cylinder to the low-pressure cylinder on line 2 2 on Fig. 1. Fig. 4 is a plan of the pipe and receivers connecting the two cylinders as it would appear if straightened out so as to lie in a flat plane. Fig. 5 is an elevation of the same receivers and pipe when in their normal or bent condition and viewed from a position at the left of Fig. 1. Fig. 6 is a transverse section of one of the receivers on line 3 3 on Fig. 4. Fig. 7 is a plan of the converting-valve casing. Fig. 8 is a vertical section on line 4 4 on Fig. 7.

Fig. 9 is an elevation of the flanged inner face of said converting-valve casing, and Fig. 10 is a plan of the lower head of said valve-casing and inlet-pipe for live steam.

My invention is illustrated in the accompanying drawings as applied to a locomotive, only so much of said engine being shown as is necessary to illustrate my invention; but the principal features of my invention are equally as applicable to stationary as to locomotive engines.

In the drawings, A represents the shell of the locomotive-boiler; A', the tube-sheet at the rear of the smoke-box.

B is the high-pressure cylinder; B', its saddle; B², its steam-chest, and B³ the steam-chest cover.

C is the low-pressure cylinder, C' its saddle, C² its steam-chest, and C³ the steam-chest cover.

D is the steam-supply pipe, through which live steam passes from the steam-dome to the steam-chest of the high-pressure cylinder.

B⁴ is the exhaust-passage of the high-pressure cylinder, to the upper end of which is connected the pipe E, which has its upper end curved toward the front of the engine and its open end inclined to form a valve-seat, as will be presently explained. The curved upper end of the pipe E projects into the lower end of the pipe E', which is firmly secured with a steam-tight joint to the collar a on said pipe E, as shown in Fig. 3. The pipe E' is forked or divided at b into two branches E² and E³, to the upper ends of which are bolted the enlarged receiver-pipes E⁴ and E⁵, respectively, the lower ends of which communicate, respectively, with the supply-passages F and F', leading to the interior of the low-pressure steam-chest C², as shown in Figs. 1 and 2.

G is the exhaust-passage of the low-pressure cylinder communicating at its upper end with the exhaust-pipe G', of usual construction.

The pipe E' has a branch opening in its side just above its connection to the pipe E, surrounded by a flange, the outer face of which is inclined to a vertical plane, with its upper portion farthest from the center line of said pipe, said opening being closed by the cover E⁶, provided upon its inner face with the annular valve-seat b, preferably in the form of a removable ring of asbestos, upon

which the annular rib *c* on the intercepting-valve *H* is seated when steam is passing from the high-pressure cylinder to the low-pressure cylinder through the pipes *E*, *E'*, *E²*, and *E³* and the receivers *E⁴* and *E⁵*. The valve *H* is mounted upon the pivot-pin *d*, set in the pipe *E'*, and has secured to its inner face an annular packing *e*, preferably of asbestos, which, when said valve *H* is moved away from the seat *b*, rests upon the inclined upper end of the pipe *E* and closes communication between the pipes *E* and *E'*. The cover *E⁶* has an opening *f* through its center, into which is screwed one end of a pipe *g*, the opposite end 15 of which communicates with the interior of the converting-valve casing *I*, secured to the exterior of the smoke-box, as shown in Fig. 1. The casing *I* has its upper end closed by the cap *I'*, in the center of which is to be 20 screwed an oil-cup, (not shown,) and its lower end has secured thereto the elbow-pipe *I²*, the upper end of which forms a valve-seat *g'*, upon which the valve *J* rests when in its normal position.

25 The interior of the casing *I* is divided into two chambers *I³* and *I⁴* by the horizontal partition *I⁵*, in the center of which is formed a bearing for the valve-rod *J'*, which extends some distance above said bearing, and has 30 firmly secured thereon the piston *J²*, of considerably larger area than the valve *J* and fitted to work steam-tight in the chamber *I⁴*, as shown. The partition *I⁵* has an annular lip *h*, projecting downward therefrom to serve 35 as a valve-seat, against which the upper side of the valve *J* is seated when it is forced upward by live steam entering through the pipe *I²* and limit its upward movement. The lower end of the pipe *I²* communicates through the 40 pipe *h'* with the interior of the steam-supply pipe *D*, as shown in Figs. 1 and 3. The upper part of the chamber *I⁴* of the converting-valve casing *I* is connected by the pipe *h²* with the interior of the pipe *E*, as shown in 45 Figs. 1 and 3, and the lower part of said chamber has inserted therein at *i* a waste-pipe to convey away any water of condensation which may be deposited therein, or any steam that may find its way past the partition *I⁵* between 50 the valve-rod *J* and its bearing. The receivers *E⁴* and *E⁵* are strengthened by means of the partitions *j*, one or more, as shown in Fig. 6.

The operation of my invention is as follows:

55 The parts being in the positions shown in the drawings and it being desired to start the engine, the engineer opens the throttle-valve, when live steam passes through the pipe *D* to the high-pressure steam-chest and at the 60 same time live steam passes through the pipes *h'* and *I²* to the under side of the valve *J*, which it moves upward till its upper packing-ring is seated against the annular lip *h*, thus opening a free passage of the live steam 65 through the pipe *g* to the center of the intercepting-valve *H*, which it moves to the right of Fig. 3, till it is seated upon the upper end

of the pipe *E*, so as to close it steam-tight, the live steam continuing through the pipes *E'*, *E²*, *E³*, receivers *E⁴* and *E⁵*, and the supply- 70 passages *F* and *F'* to the interior of the low-pressure steam-chest. By this means the engine is sure to start at once, even though the crank of the high-pressure engine should have been stopped upon its dead-center. When 75 the high-pressure cylinder exhausts, a portion of the exhaust-steam passes through the pipe *h²* to the interior of the chamber *I⁴*, above the piston *J*, and by virtue of the difference of area between said piston and the valve *J* said valve 80 *J* will be moved downward upon its seat on the end of the pipe *I²* and the live steam is shut off from the interior of the converting-valve casing *I* and remains so shut off until the next time it becomes necessary to start the engine. 85 The valve *J* has secured to its under side an annular packing-ring *k*, preferably of asbestos, to rest upon the seat *g'* when said valve is in its normal position, and to its upper side a similar ring *k'* to co-operate with the seat 90 *h* to limit its upward movement, said packing-ring also serving to lessen the shock of the blow when said valve is suddenly moved upward.

The advantages of this invention are the increased effectiveness of the low-pressure engine due to the greater area of the pipes leading from the high to the low pressure cylinders exposed to the hot gases, cheapness of construction, and effectiveness in operation. 100

I claim—

1. In combination with the high and low pressure cylinders of a compound engine, their steam-chests and steam-passages, a communicating passage between said cylinders, comprising a forked pipe having a single opening communicating with the exhaust of the high-pressure cylinder, and two branches therefrom having an aggregate area of cross-section and exterior surface greater than the initial or single portion of said pipe, as set forth. 105

2. In combination with the high and low pressure cylinders of a compound engine, their steam-chests and steam-passages, a communicating pipe connecting said cylinders, comprising a single pipe for a short distance at one end and two parallel branches forking therefrom and having an aggregate area in cross-section much greater than the area of the single initial portion thereof, said branches having a portion of their length expanded to a much larger area of cross-section to form receivers, as described. 115

3. In combination with the high and low pressure cylinders of a compound engine, their steam-chests and steam-passages, a pipe communicating with the exhaust-passage of the high-pressure cylinder at one end and having its other end curved and terminating 125 in an inclined plane and provided with a collar below said inclined end, a second pipe inclosing said curved and inclined end and secured to said collar and provided with a side 130

opening, a bonnet or cover for closing said opening, having an annular valve-seat upon its inner face, a clapper-valve pivoted within said second pipe in position to be seated upon the valve-seat on the inner face of said cover, or upon the oblique upper end of the first pipe, the converting-valve J, its casing I, the piston J², the pipe D, for supplying live steam to the high-pressure steam-chest, the pipes h' and I², connecting the interior of the pipe D with the under side of said valve J, the pipe g, connecting the interior of the chamber I³ of the converting-valve casing with the interior of the pipe E', and the pipe h², connecting the interior of the pipe E with the interior of the chamber I⁴ above the piston J², substantially as described.

4. In a compound engine, the combination, with the high and low pressure cylinders and a steam-pipe connecting said cylinders, of an intercepting-valve comprising two seats arranged at an angle to each other and each inclined from a perpendicular plane in opposite directions, with their lower sides nearest to each other, and a clapper-valve mounted upon a pivotal axis between said seats and constructed and arranged to be alternately moved in opposite directions by the pressure of steam, and to rest upon and close the pas-

sage through each of said seats, according as the flow of steam is through one or the other of said seats.

5. In combination with the high and low pressure cylinders of a compound engine, the pipe E, having its upper end curved and cut oblique to its axis to form a valve-seat, the pipe E', constructed and arranged to inclose the curved oblique upper end of said pipe E, and provided with a lateral opening closed by a removable bonnet, an annular seat on the inner face of said bonnet inclined from a perpendicular plane in a direction the opposite of the plane of inclination of the oblique end of the pipe E, a clapper-valve pivoted between said two seats in a position to co-operate with each of said seats and to be held thereto by the pressure of steam, assisted by the force of gravity, and the pipe g for admitting live steam through said bonnet and closing said valve on the end of said pipe E.

In testimony whereof I have signed my name to this specification, in the presence of two subscribing witnesses, on this 24th day of May, A. D. 1890.

FRANCIS W. DEAN.
